LATCH CONSTRUCTION

Henry J. Landry, Ashburnham, Mass.

Application April 11, 1956, Serial No. 577,510

8 Claims. (Cl. 16—144)

This invention relates to a new and improved latch construction particularly adapted for latching together in aligned condition the folding side walls of a folding playpen or the like, said walls when unlatched being capable of pivoting into side-by-side relationship for folding the playpen, and when extended, these walls are automatically latched in aligned position for use of the playpen.

Objects of the invention include the provision of a latch of the class described comprising a pair of articulated hinge members, each of which is secured to a portion of an articulated wall member adapted for pivoting into side-by-side or extended aligned condition with respect to each other, one hinge member being provided with a cam nose extending therefrom into the range of the other member and the latter being provided with means for automatically latching the same when the sections of the wall are pivoted into the aligned extended condition thereof.

Further objects of the invention include the provision of an automatic latch as above described including extremely easily operated means for releasing both latches, there being one at the break of each folding side wall, said means comprising an extension upon one of the hinge members of each latch, said extensions each being in position to be operated by a single finger of the operator merely by pressing upon the same in a direction toward the operator, whereby the hands of the operator are normally and naturally in a position for swinging in the in-swinging articulated side walls of the playpen to side-by-side relationship as above described; and the provision of a novel latch having a construction to allow positioning of upright spindles for the side walls closely adjacent the hinge members.

Other objects and advantages of the invention will appear hereinafter.

Reference is to be had to the accompanying drawings, in which

Fig. 1 is a plan view of a play-yard to which the present invention is applied to illustrate the positions of the latches;

Fig. 2 is an enlarged diagrammatic view illustrating the operation of the device;

Fig. 3 is a view in side elevation, looking in the direction of arrow 3 in Fig. 2;

Fig. 4 is an enlarged section on line 4—4 of Fig. 3;

Fig. 5 is an enlarged section on line 5—5 of Fig. 4;

Fig. 6 is a section on line 6—6 of Fig. 5;

Fig. 7 is a perspective view of one of the parts of the latch;

Fig. 8 is a sectional view illustrating the operation of the latch; and

Fig. 9 shows the latch with the side walls folded.

Although the present latch is shown as applied to a play-yard as illustrated in Fig. 1 herein, this latch may of course be used in any relationship where it is found desirable or convenient without departing from the scope of the present invention. In Fig. 1, there is

2

shown a plan view of a play-yard which has a rigid front wall 10, a rigid rear wall 12, and a pair of in-swinging side walls made up of articulated parts, the top rails of which are indicated at 14 and 16 on the one hand and 18 and 20 on the other hand. These parts are articulated by means of the latch to be described and forming a part of the invention in the present case and they are also pivoted as by hinges generally indicated by the reference numeral 22 to the respective ends 10 of the front and rear walls as is well known in the art.

The floor of the playpen is illustrated at 24 and 26, the floor part 26 having a free edge and the floor part 24 being hinged at its opposite edge to the front wall 10 at the lower portion thereof. There is a lever or the like 28 which may be utilized to extend and retract the floor and this may be constructed as further described in my copending application Serial No. 577,515, filed April 11, 1956.

The above description is merely to illustrate the use 20 and operation of the present invention which comprises in general a pair of hinge leaves 30 and 32 joined by a pintle 34 received in ferrules 36, the latter being offset from the plane of the hinge leaves as shown in Figs. 2 and 9 to provide for accommodation of parts of the 25 device when in the folded condition of the side wall members 18 and 20 and 14 and 16.

The latch described is shown as applied to the left-hand members 18 and 20 of the play-yard but the opposite latch which is generally indicated at 38 in Fig. 1 is exactly the same merely being turned up-side down in order to provide for a right-hand and left-hand operated latch for the convenience of the operator folding the playpen.

The hinge leaf 30 is secured as by conventional fasteners 40 to the member 18 of the play-yard, this being the upper rail thereof as will be understood by those skilled in the art. This upper rail member 18 is provided with an inwardly-extending slot best seen in Fig. 4 and indicated at 42. Extending into this slot is a 40 latching plate 44 which is made integral with hinge leaf 30 or is secured thereto as by welding or peening as indicated at 46. In any event, the latching plate 44 is normal to the hinge leaf 30 and it extends beyond the pintle 34 as clearly shown in Figs. 4 and 8 for entry into a transverse slot 46 which is provided in the end 45 of the side wall member 20 centrally thereof.

The hinge leaf 32 is secured to the member 20 by similar fasteners 48 and this hinge leaf covers the slot 46 at one side of the member 20 as the hinge leaf 30 covers the slot 42. Slot 42, however, need not extend all the way through member 18 but the slot 46 does so extend.

Upon the outer face of hinge leaf 32, there is fixedly mounted a block generally indicated at 50, see particularly Fig. 7. This block is undercut at its edges at 52 and also at its rear edge as at 56. The block is secured by any means such as rivets 58 extending through holes 60 into the hinge leaf 32, see Fig. 4. The block 50 is provided with a spring or springs which may be conveniently located in holes 62 in the block or otherwise and these springs are illustrated at 64 extending outwardly from said holes toward the hinge pintle 34.

A metal housing generally indicated at 66 is provided with sides 68 which are in-turned at 70 to underlie undercut portions 52 and 54 and this provides for a guided sliding action of the housing 66 relative to the block 50. Housing 66 also has a forward wall bent down at 76 so that front block 50 is enclosed and the spring 64 bears upon the inner surface of wall 76, thus normally but yieldingly holding the entire housing to the left in Figs. 3 and 4, wherein the terminal portion 74 of rear wall 72 is firmly held under the undercut portion 56.

The latching plate 44 extends to the right as seen in Fig. 4 and it terminates in a laterally extending cam nose indicated at 78. This cam nose is projectible through a slot 77 in fringe leaf 32 and into a slot 79 in block 50. This cam nose is provided with an inwardly extending notch 80 and this is the latching notch which cooperates with the inner terminal edge of the terminal portion 74 to latch the parts together. The cam portion of the nose 78 is indicated at 82, see particularly Fig. 8.

Assuming that the parts are latched together as indicated in Figs. 1, 3 and 4, the operator who stands adjacent the pedal 28 in front of the front wall 10, merely bends over slightly and places the forefinger of the left hand upon the housing 66 at the left in Fig. 1 and the forefinger of the right hand on the housing 66 at the right hand in Fig. 1, gently pulling these toward him. At the same time, the operator steps upon the pedal 28 raising the floor parts 24 and 26 as shown in the copending application above identified. Since the terminal portion 74 has now been retracted from the notch 80, see Fig. 8, the hands are then moved toward each other folding in the side walls (see the arrows, Fig. 1) behind the folding floor, the floor assuming a position in parallel folded condition with respect to front wall 10. Continuing the motion of the two hands, the in-folding side walls are brought into overlapping folded relation with respect to the folded floor parts.

Upon extending the playpen for use, the operator merely pushes the rear wall outwardly, and moves the swinging side walls at 16 and 20 oppositely to the direction of the arrows in Fig. 1. The floor then extends to a horizontal condition and when the side walls members 18 and 20 and 14 and 16 become aligned, the cam noses of the latches automatically retract the housings 66 as in dotted lines in Fig. 8, and the terminal portions 74 of housings 66 snap into the notches 80, whereupon the parts are fully automatically latched together.

This invention provides the easiest operated folding play-yard of any construction and the easiest operated latching mechanism. Only a very slight pressure of the fingers is required to unlatch the members and nothing on the part of the operator is required to be done at all in order to latch them, except to unfold the pen. There is no mechanism underneath the top rails of the side walls 14, 16 and 18 and 20 and there is no mechanism at the inside of the play-yard at all, all of the latching mechanism being at the outside aspects of the side wall members as clearly shown. The operating mechanism is not in a position where it may be accidentally actuated by the occupant of the play-yard; there is no fumbling about on the part of the operator to find the actuating member, i.e. housing 66, as is the case when the actuator is located underneath the rail; and the latch itself is extremely easy to be operated by anyone without danger of pinching the fingers in any way, the actuation of the latches being extremely smooth and easy and positioned in a novel manner relative to the folding side walls for operation in a natural manner.

The construction is such as to allow the use of spindles 84 close to the hinge, and this cannot be done in prior art structures using automatic hinges.

Having thus described my invention and the advantages thereof, I do not wish to be limited to the details herein disclosed, otherwise than as set forth in the claims, but what I claim is:

1. An automatically latching hinge construction for a pair of members articulated by the hinge comprising a pair of interpivoted hinge elements each secured to a respective member, an extension on one element extending toward the other hinge element, the latter having a slot receiving the extension when the articulated members are aligned, a movable latch in the form of a closed housing on the other element, means on the extension causing retraction of the latch when the extension moves into said slot, means on the extension to latchingly receive the latch,

5 fixed means on a member movably mounting the latch-housing, the latter being exposed and accessible for manual manipulation to release the extension, and a spring to spring-press the latch-housing, the spring being concealed in the latch housing, said fixed means also mounting the spring.

2. An automatically latching hinge construction for a pair of members articulated by the hinge comprising a pair of interpivoted hinge elements each secured to a respective member, an extension on one element extending toward the other hinge element, the latter having a slot receiving the extension when the articulated members are aligned, a slidable latch in the form of a closed housing on the other element, a fixed abutment, a spring thereon, the spring and abutment being located in the housing, the spring urging the housing to latching condition, means on the extension causing retraction of the spring-pressed latch when the extension moves into said slot, means on the extension to latchingly receive the latch, said extension being located at one side of its hinge element and the spring-pressed latch being located at the respectively opposite side of the other hinge element, the latch housing being located at said opposite side and receiving the extension therein.

25 3. An automatically latching hinge construction for a pair of members articulated by the hinge comprising a pair of interpivoted hinge elements each secured to a respective member, an extension on one element extending toward the other hinge element, the latter having a slot receiving the extension when the articulated members are aligned, a slidable housing on the other element, said housing forming a latch, a spring in the housing to urge it to latching position, means on the extension causing retraction of the housing when the extension moves into said slot, and means on the extension to latch with the housing, said extension being located at one side of its hinge element and the housing being located at the respectively opposite side of the other hinge element, a slot extending through the articulated member upon which the said slotted hinge element is mounted, said slots coinciding to receive the extension through both slots.

4. A latching hinge construction for a pair of members articulated by the hinge comprising a pair of interpivoted hinge elements each secured to a respective member, an extension on one element extending toward the other hinge element, the latter having a slot receiving the extension when the articulated members are aligned, a manually retractable housing on the other element, said housing forming a latch, means on the extension causing retraction of the housing when the extension moves into said slot, and means on the extension to latch with the housing, said extension being located at one side of its hinge element and the housing being located at the respectively opposite side of the other hinge element, and means mounting the housing for sliding motion on the said slotted hinge element.

5. A latching hinge for a pair of members arranged for alignment or selective swinging motion by the hinge, said latching hinge comprising a first hinge leaf secured to one member, a second hinge leaf secured to the other member, a pivot hinging the leaves together, an extension on the first hinge leaf extending past the pivot to engage the second hinge leaf in aligned condition of the members, the second hinge leaf having a slot to receive a part

65 of the extension, a latch associated with the slotted hinge leaf and a reception means therefor on the extension, said latch being manually retracted to release the extension, the extension being located normal to the hinge leaves, a manually slidable housing, the latch forming a part thereof, a mount on the second hinge leaf, a slot in the mount coincident with the first-named slot to receive the extension in latched condition, said latch being located in the housing, and the housing concealing the latch, extension, and mount.

70 6. The latching hinge of claim 5 wherein the members

are elongated, and there being an offset on each leaf, said offsets being laterally located relative to the members and containing the pivot.

7. The latching hinge of claim 5 wherein the extension lies partly within a member and extends outwardly thereof at its end.

8. An automatically latching hinge construction for a pair of members articulated by the hinge comprising a pair of interpivoted hinge elements each secured to a respective member, an extension on one element normal thereto and extending toward the other element when the articulated members are aligned, a spring-pressed movable housing including a latch fixed thereto on the other hinge element, a cam on the extension causing retraction of the spring-pressed housing and latch when the extension moves

10

15

to a position to engage the latch, the extension being provided with a slot adjacent said cam to receive a portion of the latch, said housing forming means for digital operation of the latch to release the extension, a fixed mount for the housing on the said other hinge element, said housing enclosing the mount and concealing the same.
